UNITED STATES PATENT OFFICE.

CLARENCE A. BODDIE, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRIC-CURRENT METER.

1,303,241.

Specification of Letters Patent.

Patented May 13, 1919.

Application filed April 4, 1916. Serial No. 88,972.

To all whom it may concern:

Be it known that I, CLARENCE A. BODDIE, a citizen of the United States, and a resident of Pittsburgh, in the county of Allegheny 5 and State of Pennsylvania, have invented a new and useful Improvement in Electric-Current Meters, of which the following is a specification.

My invention relates to electric-current 10 meters and particularly to escapement devices for such meters that are electromagnetically controlled in accordance with any desired conditions.

The object of my invention is to provide 15 an escapement device of the above indicated character that shall have electromagnetic means for controlling or restoring its oscillating member in accordance with any desired conditions.

20 My copending U. S. application, Serial No. 88,974, filed on even date herewith, discloses an escapement device for a meter having a non-restrained balance wheel that permits its oscillating member to be controlled 25 in accordance with the force applied to its escapement wheel, or, in other words, in accordance with the square of the current traversing the main winding of the meter.

The ordinary clock escapement device is 30 usually provided with a hair spring that permits the main spring of the clock to be released at a constant rate. Such an escapement device would not be applicable to measuring instruments where it is desired to 35 so control the oscillations of the movable member of the escapement device that it will oscillate in accordance with predetermined varying conditions. In view of the above, I provide a restoring or controlling device for 40 the oscillating member of an escapement device comprising a magnetizable member and a winding that tends to yieldingly hold the magnetizable member in a predetermined position. I connect the magnetizable member 45 to the double pallet or the oscillating member of the escapement device to thus control its operation in accordance with the current traversing the winding. Such an escapement device may be used to retard the 50 time of movement of a movable member of a maximum-demand meter, or it may be used to so damp the movement of the movable member of an ampere-hour meter that it will rotate more nearly in accordance with the 55 current traversing its windings.

The single figure of the accompanying drawing is a diagrammatic view of an escapement device embodying my invention.

An electrical measuring instrument 1, in connection with which my escapement device 2 may be used, comprises a magnetizable core member 3, a main winding 4, auxiliary windings 5 and 6 and an armature 7 that is mounted on a shaft 8 upon which a pointer 9 is also mounted.

60 A gear wheel 10 is mounted on the shaft 8 and is adapted to engage a pinion 11 that is mounted on a shaft 12. An escapement wheel 13 is also mounted on the shaft 12 and is adapted to coöperate with a double 65 pallet 14 that is pivoted on a shaft 15. The double pallet 14 is provided with a forked end 16. The magnet winding 17 loosely surrounds a pivoted magnetizable core member 18 that is provided with a pin 19 which 70 is adapted to be disposed between the spaced-apart portions of the forked end 16 of the double pallet 14. The windings 4 and 17 are connected in series with a conductor 20 of a circuit 21, and the windings 5 and 6 are 75 connected in a closed circuit with respect to 80 each other.

If the escapement device 2 were not provided, and current traversed the circuit 1 and the armature 7, the pointer 9 would be 85 moved in accordance with the square of the current traversing the circuit 21. If an ordinary hair-spring escapement device were connected to the shaft 8, the pointer 9 would be retarded a constant amount. However, 90 this is not desired, but, on the contrary, it is desired to retard the pointer 9 in accordance with some variable condition or force, and, in this instance, the retardation should be such that the pointer 9 will move in accordance 95 with the current traversing the circuit 21. Since the magnetizable core member 18 tends to assume a central position in accordance with the current that traverses the winding 17, its vibration or restoring force 100 may be assumed to vary substantially in accordance with the square of the current traversing the circuit 21. Thus, the pointer 9 will move in accordance with the current traversing the circuit 21.

105 When the escapement device 2 is used, the escapement wheel 13 will tend to turn in accordance with the torque of the armature 7 and will, consequently, cause the double pallet to move in one direction. When the 110

double pallet moves, the movable core member 18 will be moved from its normal position, and the current traversing the winding 17 will cause it to return to its normal position to move the double pallet in the opposite direction. In this manner, the double pallet 14 may be caused to so oscillate that the pointer 9 will move in accordance with the current traversing the circuit 21.

10. While I have illustrated my invention in connection with a particular type of meter, it will be understood that it is not so limited, as many modifications may be made in my invention within the spirit and scope of the 15 appended claims.

I claim as my invention:

1. The combination with a rotatable member and an electromagnetic actuating means therefor, of an escapement device operatively connected to the movable member and having a controlling means actuated in accordance with the current traversing the electro-magnetic means.

2. The combination with a rotatable member and an electromagnetic actuating means therefor, of an escapement wheel operatively connected to the movable member, a double pallet for the escapement wheel, and a second electromagnetic means for controlling the double pallet in accordance with the current traversing the first electromagnetic means.

3. The combination with a movable member, of an escapement wheel operatively connected to the movable member, a double pallet for the escapement wheel, and means for controlling the double pallet in accordance with the energy that actuates the movable member.

40. 4. The combination with a movable member, of an escapement wheel operatively connected to the movable member, a double pallet for the escapement wheel, and electromagnetic means for controlling the double pallet in accordance with the energy actuating the movable member.

45. 5. The combination with a movable mem-

ber and means for actuating the same, of an escapement device for controlling the movable member, and means for controlling the escapement device in accordance with the energy of the actuating means.

6. The combination with a movable member, and means for actuating the same, of an escapement device operatively connected to the movable member, and means for controlling the escapement device in accordance with the actuating force of the actuating means.

7. The combination with a movable member and an electromagnetic means for actuating the same, of an escapement device for controlling the movement of the movable member, and means actuated in accordance with the current traversing the electromagnetic means for controlling the said escapement device.

8. The combination with a movable member and an electromagnetic means for actuating the same, of an escapement device for controlling the movement of the movable member, and a second electromagnetic means for controlling the operation of the escapement device in accordance with the current traversing the first electromagnetic means.

9. The combination with a movable member and means for actuating the same, of an escapement wheel operatively connected thereto, a double pallet for the escapement wheel, and means for opposing the oscillating of the double pallet in accordance with the torque of the movable member.

10. The combination with a movable member and means for actuating the same, of an escapement wheel operatively connected thereto, a double pallet for the escapement wheel, and electromagnetic means for controlling the oscillating of the double pallet in accordance with the torque of the movable member.

In testimony whereof, I have hereunto subscribed my name this 27th day of March 1916.

CLARENCE A. BODDIE.
